(57) **CLAIM**

The ornamental design for a desk bracket, as shown and described.

DESCRIPTION

FIG. 1 is a perspective view showing the rear, left side, and top of a desk bracket showing my new design;

FIG. 2 is an enlarged perspective view thereof; and,

FIG. 3 is a left side elevational view thereof.

The right side elevational view is a mirror image of the left side. The front side elevational view is a mirror image of the rear. The bottom view is not shown because it forms no part of the claimed design. The desk parts and attachment hardware are shown in broken lines for illustrative purposes only and form no part of the claimed design.

The characteristic feature of the design resides in the application of a part having the appearance of an automotive tower strut bar to the desk bracket.
